Primary Examiner — Elizabeth J Oswecki*(74) Attorney, Agent, or Firm* — Millen, White, Zelano & Branigan, P.C.(57) **CLAIM**

The ornamental design for a jumbo turner, as shown and described.

DESCRIPTION

FIG. 1 is a top plan view of a jumbo turner showing our new design;

FIG. 2 is a bottom plan view thereof;

FIG. 3 is a back view thereof;

FIG. 4 is a front view thereof; and,

FIG. 5 is a side view thereof.

All surfaces not shown form no part of the claimed design.
